UNITED STATES PATENT OFFICE.

HARRY E. HARRIS, OF BRIDGEPORT, CONNECTICUT.

GRINDING WHEEL.

1,422,200.

Specification of Letters Patent. Patented July 11, 1922.

Application filed April 14, 1919. Serial No. 289,963.

To all whom it may concern:

Be it known that I, HARRY E. HARRIS, a citizen of the United States, residing at Bridgeport, county of Fairfield, State of Connecticut, have invented an Improvement 5 in Grinding Wheels, of which the following is a specification.

This invention relates to an improved grinding wheel and has for its object to provide such a wheel having a large mass and moment of inertia so that it will rotate accurately on its axis. Another object is to provide a grinding wheel composed of a wheel of steel or other metal carrying a disc 10 or ring of abrasive material on its periphery. A further object is to provide a wheel or ring of abrasive material varying in hardness in an axial direction, the hardest portion being preferably at the point of 15 greatest diameter of the wheel, at the center thereof in the example illustrated.

With these and incidental objects in view, the invention consists in certain novel features of construction and combination of 20 parts which are set forth in the appended claims and a preferred form of embodiment whereof is hereinafter described with reference to the drawings which accompany and form part of the specification, wherein:

30 Fig. 1 is a side elevation of a grinding wheel embodying my invention, and

Fig. 2 is a sectional view taken on the line 2—2 of Fig. 1.

In said drawings the numerals 11 designate suitable bearings supported by bearing standards 12 mounted on the base 13. Said bearings receive the shaft 14 upon which the heavy gyro wheel 15, preferably formed of metal, is carried. This wheel may be of any 40 desired form except that the mass is preferably located as near the rim as possible to increase its moment of inertia. For this purpose the wheel may be formed with a heavy rim 16 the part 16' of which may be 45 removably attached thereto by suitable means as bolts 17 to clamp therebetween the disc or ring of abrasive material 18 in the recess 19. The disc or ring 18 may be formed of any suitable abrasive as emery, 50 diamond dust, carborundum, corundum, etc., but is preferably formed of harder material

near its point of greatest diameter as shown by the darker portion 18'. Any suitable means may be provided for rotating the wheel at a very high speed.

In practice the gyro wheel 15 is very carefully made and accurately balanced, so that the center of mass coincides as nearly as possible with the axis of the rotating parts. On this account and on account of its great 60 weight and large moment of inertia the wheel rotates very accurately in spite of possible play or looseness in the bearings. This is due in part to the well known tendency of a gyro wheel to resist a change in its plane 65 of rotation. A further reason probably is, that as the "critical speed" of such a wheel is very low it will ordinarily operate far above this speed and its operation is therefore free from the vibration generally present when bodies are rotated below or near their "critical speed."

A further advantage is that a relatively small amount of abrasive material is necessary to secure the advantages of a grinding 75 wheel of large diameter and a much smaller amount of abrasive is wasted. By forming the section corresponding to the position of largest diameter of harder material the wheel is better able to retain its original 80 contour as the greater tendency to wear at the point of greatest diameter is compensated for by greater durability at this point.

It will be seen that I have provided a construction which fulfills the objects previously stated and while I have shown and described a specific embodiment of my invention it is to be understood that changes and modifications thereof may be made without departing from my invention as defined in 90 the following claims:

I claim:

1. A grinding device comprising a gyro wheel having a wide, substantially flat, heavy periphery composed of two sections 95 substantially equal in mass, one of said sections having a peripheral recess, a ring of abrasive material mounted in said recess, and means to clamp the other of said sections against said ring and ring holding section.

2. A ring of abrasive material having por-

tions of its grinding surface of greater diameter than other portions, the portions of greater diameter being composed of harder material to resist wear and preserve the 5 tour of the ring.

3. A grinding device comprising a gyro wheel and a ring of abrasive material car-

ried thereby, portions of the grinding surface of said ring being of greater diameter than other portions, the portions of greater 10 diameter being composed of harder material.

In testimony whereof I affix my signature.
HARRY E. HARRIS.
